UNITED STATES PATENT OFFICE.

LEO WILOTH AND ALBERT L. GREER, OF DENVER, COLORADO; SAID WILOTH
ASSIGNOR TO SAID GREER.

BATH-CABINET.

1,240,911.

Specification of Letters Patent. Patented Sept. 25, 1917.

Application filed May 22, 1916. Serial No. 99,114.

To all whom it may concern:

Be it known that we, LEO WILOTH and ALBERT L. GREER, citizens of the United States, residing at Denver, in the county of Denver and State of Colorado, have invented certain new and useful Improvements in Bath-Cabinets, of which the following is a specification.

Our invention relates to bath cabinets and its principal object resides in providing in combination with a chamber adapted to admit part or all of a human body, a system of conduits, valves, vaporizing appliances and other devices which are coöperatively associated to introduce into the chamber, vapors of different character either singly or together, or to heat the same to different degrees of temperature by adjustment of one or more of the valves included in the system.

Another object of our invention resides in providing an adjustable shield by which one or more parts of a reclining body may be subjected, exclusive of other parts of the same, to the vapors or heat introduced into the chamber.

The above and other objects all of which will be fully described in the course of the following description, we attain by the arrangement of devices illustrated in the accompanying drawings in the various views of which like parts are similarly designated, and in which,

Figure 1 is a vertical section through the improved bath cabinet,

Fig. 2, a transverse section along the line 2—2, Fig. 1,

Fig. 3, a transverse section along the line 3—3, Fig. 2, drawn to an enlarged scale,

Fig. 4, an enlarged section through the bed or supporting surface of the apparatus showing the application of the shield hereinbefore referred to,

Fig. 5, a fragmentary face view of the shield,

Fig. 6, a fragmentary section through the rear wall and lid of the cabinet, showing means for covering the space between the adjoining edges thereof against the outflow of liquid, and

Fig. 7, a horizontal section through one of the containers comprised in the vaporizing elements of our invention.

Referring more specifically to the draw-

ings, the reference numeral 2 designates the body of the cabinet which consists as usual of a preferably rectangular box, and 3 a lid which normally covers the same.

The box has in one of its ends an opening 4 and exteriorly thereof an adjustable rest 5 for the head of a patient reclining in the cabinet.

The lid is connected with the box along one of its longitudinal edges, and a hinged apron 6 attached to the lid is adapted to cover the space between the adjoining edges of the box and the lid against the outflow of liquid when the lid is in its open position as shown in Fig. 6 of the drawings.

A bed 7 composed of transversely spaced slats is disposed in the box at a distance above its bottom, for the support of a human body in a reclining position.

The bed divides the chamber into two compartments 8 and 9 the lower one of which contains a system of conduits adapted to supply heat or vapors to the upper or vapor compartment, through the spaces between the slats of which the bed is composed.

The lid has a normally covered opening 10 through which the interior of the box may be reached or observed without opening the lid, and it has in suitable proximity to said opening, a gage 12 to indicate the temperature of the vaporizing chamber.

The box is supported upon legs 13 and it has in its bottom an outlet 14 for the drainage of liquid of condensation, which if so desired may be permanently connected with a sewer or other distant receiver by means of a conduit 15.

Secured exteriorly of the box are a number of vaporizing elements which in the operation serve to produce and discharge into the chamber, vapors of medicinal preparations.

Each vaporizing element comprises a container 16 connected by means of a valve-controlled pipe 17 with a superposed reservoir 18 which preferably is made of glass and provided with a scale of graduations 19 by which the quantities of liquid admitted to the container by opening the valve in the respective conduit, may be accurately measured.

A coil 20 disposed within the container is provided for the vaporization of the liquid

contents of the same and is to this end, connected with a source of steam or other heating fluid as will hereinafter be more fully described.

5 Placed within the compartment 8 of the cabinet beneath the slotted bed 7, is a system of conduits which include a central vapor-escape pipe 21, a primary heating coil 22, and a secondary or auxiliary heating coil 23.

10 The two coils are connected for the passage of a heating fluid from one to the other, and valves are applied to the coils to permit of a flow of fluid through one, exclusive of the other.

15 The connected coils connect at their outer ends with a source of heating-fluid supply and with an exhaust or waste conduit.

20 The inlet ends of the coils 20 of the vaporizing elements are exteriorly of the containers 16, connected with valves 24 which by means of a manifold 25 are connected with a branch of a fluid-supply pipe 27 which connects with a boiler or other source 25 of heated air or steam, not shown in the drawings.

25 A pipe 28 connects the supply pipe with the inlet end of the primary heating coil, and a branch 29 of the pipe 28 connects 30 with a manifold 30 placed beneath the cabinet and connected with the outlets of the coils 20 of the several vaporizing elements.

35 Check valves 31 in the pipes which connect the coils 20 with the manifold 30, are provided to prevent the flow of fluid into the coils when the vaporizing elements are disconnected from the system as will herein- 40 after be described.

30 The primary heating coil connects at 32 with the inlet end of the auxiliary coil and by means of a pipe 33 with the vapor-escape pipe 21.

45 The outlet end of the primary coil is furthermore connected, by means of a pipe 34, with an exhaust or waste pipe 35 through which the spent heating fluid either escapes 50 into the atmosphere or is returned to the source of supply, and the outlet of the secondary heating coil is connected with the same exhaust pipe, as at 36.

55 The containers of the vaporizing elements have vapor-outlets which through the intermediary of valves 37 are connected with a manifold 38 which connects with the vapor- 60 escape pipe 21. Each container has a drain cock 39 and a safety valve 40 which prevents accidents in case of over-compression of vapors in the containers, by faulty adjustment of the valves which control the inflow and outflow of heating fluid and vapors.

65 A valve 41 is connected in the pipe 28 which connects the supply pipe with the primary heating coil, a valve 42 controls the connection between the two heating coils adjacent the point 32, a valve 43 is connected

in the pipe 33 which connects the primary coil with the vapor-escape pipe, a valve 44 controls the flow of fluid through the pipe 34 which connects the primary coil with the waste-pipe, and a check valve 45 is disposed in the connection between the secondary coil and the exhaust pipe 35.

70 By the system of conduits, vaporizing appliances and valves co-operatively associated as herein described, the following results 75 may be produced:

75 *First—The introduction of steam into the cabinet for an ordinary steam bath.*—The valves 41 and 42 are opened and the valves 44, 24, 45 and 42 are closed. The steam from the boiler flows from the supply-pipe 27 through the branches 28 into the primary coil and enters the vapor-escape pipe past the open valve 43.

80 *Second—Heating the current for the purpose of giving a dry-heat bath.*—The valves 41 and 42 are opened and the valves 43, 44 and 24 are closed. The steam flowing past the valve 41 into the primary coil passes through this coil and past the open valve 42 85 into the secondary coil through which it circulates and from which it flows past the open valve 45 into the waste-pipe 35.

90 If in administering a dry-heat bath it is desired to reduce the heat in the cabinet, the auxiliary coil may be excluded from the path of the steam by closing the valve 42 and opening the valve 44. The steam after 95 passing through the primary coil, now flows past the open valve 44 and through the pipe 100 34 which connects with the return or waste pipe 35.

105 It will be observed that in the above described operations, the check valves 31 prevent the steam from entering the coils in the containers.

110 *Third—The introduction of vapors generated in one or more of the vaporizing elements, into the cabinet for medicated vapor baths.*—Premising that the three containers 115 of the elements have been supplied with different medicinal preparations, the vapor from any one of them or from two or more of them combined, may be introduced at the will of the operator, into the cabinet which is heated by the steam exhausted from the coils in the respective container or containers.

120 To generate medicinal vapors in any one of the elements and discharge the same into the cabinet, the valves 24 and 37 of the respective container are opened and the valves 41 and 43 are closed. The steam from the supply pipe 27 now passes through the manifold 25 and past the opened valve 24 into 125 and through the coil 20 in the container and thence past the respective check-valve 31 into the manifold 30 which by means of the branch 29 is connected with the primary heating coils.

The steam is thus compelled to pass through either one or both of the heating coils as in the operation described under "Second," and is returned to the boiler or 5 exhausted into the atmosphere by means of the waste-pipe 35.

The steam passing through the coil in the container vaporizes the medicinal liquid contained therein, and the vapor thus produced 10 escapes from the container past the open valve 37 into the manifold 38 which connects with the vapor-escape pipe 21.

It will be readily understood that in this manner vapor from any one of the elements 15 may be admitted to the cabinet, that if the condition of the patient requires the administration of different medicinal substances, the vapor from two or more containers may be simultaneously introduced into the chamber, and that if so desired, steam and the vapors of one or more of the containers may be simultaneously admitted into the cabinet by closing the valves 42, and 44 and opening valve 43.

25 After a bath has been given, the cabinet can be thoroughly sterilized by the introduction of steam as in the first-described operation, it being understood that the water of condensation is constantly drained from 30 the cabinet through the outlet 14.

The pet cock 39 at the bottom of each container, permits of draining the same for the purpose of cleaning or for changing the medicinal solution.

35 The reservoirs 18 connected with the containers supply to the same, medicinal liquids which are readily measured on the graduated scales 19 and the safety valves 40 on top of the containers prevent accidents in 40 case one or more of the valves of the system are inadvertently placed in the wrong position.

To permit of the adjustment of the valves inside the cabinet from without the same, 45 their stems are socketed, and a key 46 is provided which through openings in the wall of the box, is introduced into the sockets of the valves to turn them to the required position.

50 When one of the containers is in use, the steam discharged from its coil is prevented from entering the coils of the other containers by the check valves 31, and to equalize the outflow of vapor through the apertures of the perforated escape pipe 21, the perforations are from its inlet end outwardly, gradually enlarged as shown in Fig. 2 of the drawings.

In the operation of the cabinet, the patient 55 reclines on the slotted bed with his head upon the rest outside the chamber. In administering a vapor bath, the lid 3 is closed and it is opened only when it is desired to rub or wash the body of the patient.

65 When the patient is being washed, which

usually is done by the use of a spray, the apron 6 closing the space between the adjoining edges of the open lid and the box, prevent the water from splashing through said space onto the floor of the room in 70 which the cabinet is installed.

A shield 47 shown in Figs. 4 and 5 is used in the treatment of any particular part of the human body, exclusive of other parts.

The shield consists of a plate which is 75 adapted to cover the pipe system in the compartment 8 of the cabinet, beneath the slotted bed 7.

The plate has a plurality of openings 48 which in position and size correspond with 80 different parts of a body reclining on the bed, as for example, the shoulders, knee-joints, feet, etc.

The openings 48, with the exception of that beneath the part of the body it is desired to treat, are closed by slides 49, and a short flue 50 removably placed between the uncovered opening and the bed 7, aids in concentrating the heat or vapors to the part of the body that is being treated.

Having thus described our improved cabinet in the best and simplest form known to us, we desire it understood that variations in the arrangement of the pipes and valves of the heating and distributing system, in the number of vaporizing element applied to the cabinet, and in details of construction of the various parts of the same, may be resorted to within the spirit of my invention as defined in the following claims:

1. A bath-cabinet comprising a chamber, primary and secondary heating coils therein, a source of liquid-fluid supply, a waste pipe, a connection between adjacent ends of said coils, a connection between the source and the other end of the primary coil, a connection between the other end of the secondary coil and the waste-pipe, a connection between the primary coil and the waste pipe, and adjustable valves in said connections whereby fluid admitted to the primary coil may be compelled to flow through either the primary coil or through both the coils, into the waste pipe.

2. A bath-cabinet comprising a chamber, primary and secondary heating-coils and a vapor-escape pipe therein, a supply pipe, a waste pipe, a connection between adjacent ends of said coils, a connection between the other end of the primary coil and the supply-pipe, a connection between the other end of the secondary coil and the waste-pipe, a connection between the primary coil and the waste-pipe, a connection between the primary coil and the vapor-escape pipe, and adjustable valves in said connections, whereby the fluid admitted to the primary coil may be compelled to flow through the primary coil into the vapor-escape pipe, through the primary coil into 130

- the waste-pipe or through both coils and into the waste pipe.
3. A bath-cabinet comprising a chamber, a heating coil and a vapor-escape pipe therein, a source of heating-fluid supply, a vaporizing element including a container and a heater for vaporizing the contents thereof, connections between said heater, said source and said coil, and a connection between said element and the vapor-escape pipe whereby a heating fluid may pass from the source to the vapor-escape pipe either through the heater and the coil, or through the coil exclusive of the heater.
4. A bath-cabinet comprising a chamber, a heating coil and a vapor-escape pipe therein, a source of heating-fluid supply, a plurality of vaporizing elements each including a container and a heater for vaporizing the contents thereof, connections between the heaters of said elements and the source, connections between the containers and the vapor-escape pipe, connections between said heaters and the coil, and valves in connections, whereby the heater and container of any one of said elements may be placed in communication with the source, the coil and the escape pipe, exclusive of the other elements.
5. A bath-cabinet comprising a chamber, a heating coil and a vapor-escape pipe therein, a source of heating-fluid supply, a plurality of vaporizing elements each including a container and a heater for vaporizing the contents thereof, a manifold connected with said source, a manifold connected with said coil, connections between said manifolds and the heaters of the elements, a manifold in connection with the vapor-escape pipe, connections between the last-mentioned manifold and the containers of the elements, and valves in said connections, whereby the heater and container of any one of said elements may be placed in communication with the source, the coil and the escape pipe, exclusive of the other elements.
6. A bath-cabinet comprising a chamber, a heating coil and a vapor-escape pipe therein, a source of heating-fluid supply, a waste-pipe, a vaporizing element including a container and a heater for vaporizing the contents thereof, a connection between said source and said heater, a connection between the heater and the coil, a connection between the container and the vapor-escape pipe, a connection between an end of the coil and the source, a connection between the other end of the coil and the waste-pipe, and valves in said connections, whereby the heating fluid may be compelled to pass through the coil exclusive of the said element, or through the heater of the element and thence through the coil.
7. A bath-cabinet comprising a chamber, a heating coil and a vapor-escape pipe there-
- in, a source of heating-fluid supply, a waste-pipe, a vaporizing element including a container and a heater for vaporizing the contents thereof, a connection between said source and said heater, a connection between the heater and the coil, a connection between the container and the vapor-escape pipe, a connection between an end of the coil and the source, a connection between the other end of the coil and the waste-pipe, a connection between the coil and the vapor-escape pipe, and valves in said connections whereby the heating fluid may be compelled to pass either through the coil exclusive of said element and into the waste-pipe, through the coil exclusive of the element and into the vapor-escape pipe, or through the heater of the element and thence through the coil.
8. A bath-cabinet comprising a chamber, primary and secondary heating-coils and a vapor-escape pipe therein, a source of heating-fluid supply, a waste-pipe, a vaporizing element including a container and a heater for vaporizing the contents thereof, a connection between adjacent ends of said coils, a connection between the other end of the primary coil and the source, a connection between the other end of the secondary coil and the waste-pipe, a connection between the primary coil and the waste-pipe, a connection between the primary coil and the vapor-escape pipe, a connection between the source and the heater of the vaporizing element, a connection between the heater and the coil, a connection between the container and the vapor-escape pipe, and valves in said connections, whereby the heating fluid may be compelled to pass either through one or both of the heating coils into the waste-pipe, exclusive of the vaporizing element, through a coil and into the vapor-escape pipe exclusive of the vaporizing element, or through the heater of the element and thence through the coil.
9. A bath-cabinet comprising a chamber, primary and secondary heating coils and a vapor-escape pipe therein, a source of heating-fluid supply, a waste-pipe, a vaporizing element including a container and a heater for vaporizing the contents thereof, a connection between adjacent ends of said coils, a connection between the other end of the primary coil and the source, a connection between the other end of the secondary coil and the waste-pipe, a connection between the primary coil and the waste pipe, a connection between the source and the heater of the vaporizing element, a connection between the heater and the coil, a connection between the container and the vapor-escape pipe, and valves in said connections, whereby the heating fluid may be compelled to pass either through one or both of the heating coils into the waste-pipe, exclusive of

the vaporizing element, or through the heater of the element and thence through the coil.

10. A bath-cabinet comprising a chamber, 5 a heating coil and a vapor-escape pipe therein, a plurality of vaporizing elements each including a container and a heater for vaporizing the contents thereof, a source of heating-fluid supply, a waste-pipe, connections 10 between said source and the heaters of said elements, connections between the heaters and the coil, connections between the containers and the vapor-escape pipe, a connection between an end of the coil and the 15 source, a connection between the other end of the coil and the waste-pipe, a connection between the coil and the vapor-escape pipe, and valves in said connections whereby the heating fluid may be compelled to pass 20 through the coil into the waste-pipe exclusive of said elements through the coil and into the vapor-escape pipe exclusive of said elements, or through the heater of any one of the elements and thence through the coil 25 exclusive of the other elements.

11. A bath-cabinet comprising a chamber, a heating-coil and a vapor-escape pipe therein, a plurality of vaporizing elements each including a container and a heater for vaporizing the contents thereof, a source of heating-fluid supply, a waste-pipe, connections 30 between said source and the heaters of said elements, connections between the heaters and the coil, connections between the 35 containers and the vapor-escape pipe, a connection between an end of the coil and the source, a connection between the other end of the coil and the waste-pipe, and valves in said connections whereby the heating fluid 40 may be compelled to pass through the coil into the waste-pipe exclusive of said elements, or through the heater of any one of the elements and thence through the coil exclusive of the other elements.

45. 12. A bath-cabinet comprising a chamber, a heating coil and a vapor-escape pipe therein, a source of heating-fluid supply, a waste-pipe, a plurality of vaporizing elements each including a container and a heater for vaporizing the contents thereof, a connection 50 between an end of said coil and the source, a

connection between the other end of the coil and the waste-pipe, a manifold connection with the source, a manifold connected with the coil, connections between said manifolds 55 and the heaters of said elements, a manifold in connection with the vapor-escape pipe, and valves in said connections, whereby the heating fluid is compelled to pass through the coil into the waste-pipe exclusive of said 60 elements, or through the heater of any one of the elements and thence through the coil exclusive of the other elements.

13. In a bath-cabinet, a chamber, an element therein for the supply of heat or vapor, a bed above said element for the support of a patient, a shield above said element and spaced from said bed, said shield having a passage for heat or vapor, corresponding with a determinate part of a body 70 reclining on said bed, and a conduit connected with said passage to conduct vapors across said space to said determinate part of the body.

14. In a bath-cabinet, a chamber, an element therein for the supply of heat or vapor, a bed above said element for the support of a patient, a shield separating said element from said bed, and having a plurality of passages corresponding with determinate 75 parts of a body reclining on the bed, and means for separately closing said passages.

15. In a bath-cabinet, a chamber, an element therein for the supply of heat or vapor, a bed above said element for the support of a patient, a shield between said element and said bed, having a plurality of passages corresponding with determinate parts of a body reclining on the bed, means 80 for separately closing said passages, and a movable conduit for concentrating vapors flowing through any one of said passages to the corresponding part of the body.

In testimony whereof we have affixed our 95 signatures in presence of two witnesses.

LEO WILOTH.
ALBERT L. GREER.
